UNITED STATES PATENT OFFICE

GEORGE H. KNOWLTON, OF WESTBROOK, MAINE

VULCANIZING OR DRYING APPARATUS

Application filed April 10, 1929. Serial No. 354,050.

The invention to be hereinafter described relates to apparatus for continuous feeding of sheet material into and out of a vulcanizer or drier oven after one side of the sheet has 5 been coated with a preparation, one of the ingredients in which is rubber or any material that needs drying or vulcanizing.

In operating this class of apparatus it is essential, if a smooth and evenly dried or 10 vulcanized coating on the sheet material is to be procured, that the coated side of the sheet be always kept out of contact with the feeding rolls or other supporting elements in the sheet-feeding mechanism, and that the 15 sheet be kept in constant motion to prevent over vulcanizing or drying in any one place or sheet.

To accomplish this, which is one of the objects of my present invention, I provide a 20 plurality of driven rolls disposed in parallel relation and acting synchronously at a uniform speed, the sheet passing through the vulcanizing or drying chamber in a draped or festooned arrangement, forming loops 25 which hang suspended from between each respective pair of rolls, with the uncoated side of the sheet only contacting with the rolls.

A further object of the invention is to 30 provide means to equalize the lengths of the loops when, for instance, one of the rolls has over-fed the sheet and the loop adjacent has become distended beyond the others. I attain this object by lifting the sheet from 35 one side of the over-feeding roll, thereby shortening its contacting surface and delaying or stopping the feeding of the sheet at the said roll and thereby causing the over-fed portion to be taken up by the feeding 40 movement of the other rolls without stopping or checking the movement of the sheet as a whole through the vulcanizing chamber.

A still further object resides in the extremely large capacity of this sheet-feeding 45 mechanism, attainable by reason of the quantity of sheet material which may be taken care of in the depending loops and which allows of substantially the entire space within the vulcanizer chamber being utilized.

50 The character of the invention may be best

understood by reference to the following description, taken in connection with the accompanying drawings in which an illustrative embodiment thereof is disclosed, which at the present time I consider preferable to other possible forms in which the invention might be carried out. 55

In the drawings, in which like characters of reference are employed to identify like parts in all the different views: 60

Fig. 1 is a diagrammatical view showing the course of the coated sheet and the method of driving the rolls to feed the sheet through the vulcanizer chamber.

Fig. 2 is an end elevation of a hanger equipped with the stop-feed mechanism. 65

Fig. 3 is a side elevation of the same, and further, showing a fragmentary view of the feed-roll and drag-bar.

Fig. 4 is an assembly of three complete 70 hangers, shown in end elevation, the side wall of the vulcanizing or drying chamber being removed for convenience of illustration.

Figs. 5 and 6 are diagrammatical illustrations showing two positions of the sheet-feeding and non-feeding, respectively. 75

Fig. 7 is a fragmentary sectional detail 80 of the feed roll.

Referring to Fig. 1, A is a vulcanizing or drying chamber enclosing the entire apparatus, except for the exteriorly arranged sprockets by means of which the stop-feed mechanism is actuated, and B represents the steam pipes which supply heat for vulcanizing or drying purposes. In practice, the steam pipes B will be arranged at the bottom and the side and rear wall of the chamber, but any other suitable heating means 85 may be employed. 90

In this figure is also shown in abbreviated outline the general arrangement of the parts having to do with the feeding of the sheet, and the position which the sheet occupies as 95 it depends from one feed roll, is formed into a loop, and rises to and passes over the next feed roll, and so on, to drape or festoon the sheet to form depending loops.

The sheet S starts from the coating ma- 100

chine (not shown), and passing over the equalizing roll 1, forms into a variable compensating loop 2, the purpose of which will hereinafter be explained. After traversing 5 all of the feed-rolls 3 the sheet is finally guided out of the vulcanizer on the rolls 4 and passes on to the winding drum (not shown).

Any suitable driving means may be employed to rotate the rolls 3, but as shown in 10 the drawings it comprises the sprocket wheels 5 secured to the ends of the feed-roll shafts, and the sprocket chain 6 making a straight line drive over the tops of the 15 sprocket wheels and returning over the intermediate idlers 7 and under end idlers 7, which maintain the sprocket chain in a stretched condition.

The main drive is through the sprocket 20 chain 8 operating on a sprocket on the shaft 9. From this shaft the first feed-roll 3 is driven through the chain 10 and the winding machine drive is through the chain 11.

In Figs. 2 and 3, details of the hanger 25 and stop-feed mechanism are illustrated.

On an I-beam 12 is adjustably secured the frame 13 of the hanger, it being understood, of course, that there is a hanger on each end of the roll 3, and in the bearing 14 thereof 30 is journaled the shaft 15, integral with the roll 3, which latter is preferably tubular in form.

On the inner side of the hanger and adjustably secured thereto is the plate 16, at 35 the lower end of which, in the aperture 16' is a collar 17 in which is located the gudgeon end 18 of the drag-bar 19. This latter is circumferentially adjustable in the collar 17 upon releasing the set-screw 20.

On the surface of the roll 3 and also on 40 the drag-bar 19 are ribs 21 and 22, respectively, these ribs spiralling in different directions from the lengthwise center of the rolls and drag-bar, outwardly toward the ends thereof.

The object of this construction is for the 45 purpose of exerting a slight tension on the surface of the sheet material acting from the central portion outwardly, this tending to keep it taut and smooth.

In an arcuate slot 23, in the plate 16, is a 50 shaft 24 which extends across the vulcanizer to the corresponding plate 16 on the hanger opposite. On this shaft is fixed a 55 pinion 25 making meshing engagement with the segment of a gear 26 which is bolted to the plate 16 concentric with the arcuate slot. On the end of the shaft which projects outwardly from the vulcanizer chamber is a 60 sprocket wheel 27 operable manually by the sprocket chain 28.

The hangers are arranged in pairs, one 65 hanger on each end of each feed-roll 3, and as each is equipped with the elements just previously described, it is obvious that by ro-

tating the sprocket 27 the shaft 24 will be elevated in the slot 23 with its axis always parallel, or approximately parallel, with that of the feed-roll, and further, that when so raised, as shown in dot and dash lines in Fig. 2 and diagrammatically illustrated in Fig. 6, will cause the sheet material S to lose its grip of the feed-roll to such an extent as to stop its further movement over such feed-roll, the drag-bar 19 assisting in offering more or less resistance to forward movement of the sheet.

The operation of this stop-feed mechanism and the object in equipping the hangers therewith may be more comprehensively understood by reference to Fig. 4.

Let it be assumed that the first feed-roll 3 has, from some cause, overfed the sheet S and a longer loop 29 formed. By actuating the chain 28, the shaft 24 is raised and this delays or entirely stops further forward movement of the portion S_a of the sheet S.

But the other rolls 3 are still actively drawing the sheet forwardly and continue to do so until the bottom of the loop 29 is raised to a level with the other loops, or as shown in dot and dash lines (Fig. 4), at which point the shaft 24, which was elevated, is lowered to its normal position in the bottom of the slot 23 and the feeding of the sheet is now effected by all of the rolls in regular order.

During the time in which the sheet is idling over the first feed-roll 3 the equalizer roll 1 continues to feed the sheet forwardly, so that a length of sheet equal to the extra amount in the loop 29 is added to the variable compensating loop 2, extending it as shown at 2a.

This action may take place on any one of the rolls in the line shown in Fig. 1, and when it occurs on any of the centrally located ones, those over which the sheet has already traveled must be given the same treatment as has just been described regarding the first one, the surplus length of overfeed being eventually transferred to the variable compensating loop 2, which by proper take-up mechanism in the coating machine may be kept within bounds.

A detail in the construction of the feed roll is illustrated in Fig. 7. The roll is first grooved to receive the round wire 21, the depth of the groove 30 being somewhat greater than one-half the diameter of the wire. The roll is placed on centers, in a lathe or winding machine, and the wire tightly wound into the groove, at the same time an upsetting tool engages the surfaces t, t, rolling the shoulders of the groove firmly against the wire and rigidly securing it.

The plate 16 is adjustably secured to the hanger at 31, a slot 32 allowing the plate to be lowered or raised on a pivot 31a with a

consequent effect of moving the drag-bar 19 toward or from, respectively, a central, vertical line through the hanger bearing. The pivot 31a is located at one side of the hanger and the bolt 31 and the slot 32 are located at the other side of said hanger.

When adjustments are made at 31, corresponding adjustments are usually required to be made in the angular position of the drag-bar 19, made through relaxing the screw 20.

As will be noted by observing Figs. 2 and 3, the hangers are adjustable lengthwise of the I-beam by releasing the holding cleats 33. This is sometimes required when sheets of different pliability or thicknesses are to be coated—a difference in this pliability generally being accompanied by either greater or less space between the depending sides of the down-handling loops, necessitating, in some cases, more room between the successive folds of the material.

What is claimed:

1. An apparatus of the class described, including means for supporting a sheet of material draped or festooned to form a series of depending loops having free lower ends, the said means being arranged for continuously feeding the sheet of material for passing the same into, through and out of a drying and vulcanizing chamber, and means for varying the frictional contact between the sheet and the feeding means, whereby over-run or feed of the material in the loops may be taken up without interrupting the feed of the sheet.

2. An apparatus of the class described, including means for supporting a sheet of material draped or festooned to form a series of depending loops having free lower ends, the said means being arranged for continuously feeding the sheet of material for passing the same into, through and out of a drying and vulcanizing chamber, means for varying the frictional contact between the sheet and the feeding means, whereby over-run or feed of the material in the loops may be taken up without interrupting the feed of the sheet through the apparatus, and means for forming a variable compensating loop in the sheet, said compensating loop being arranged to receive the surplus material of the sheet from the over-feed.

3. An apparatus of the class described, including means for supporting a sheet of material draped or festooned to form a series of depending loops having free lower ends, means for varying the size of the space between the sides of the loops, the supporting means being arranged for continuously feeding the sheet for passing the same into, through and out of a drying and vulcanizing chamber, and means for varying the length of the depending loops to take

up any overfeed of the sheet and maintain the loops of a substantially uniform length without interrupting the continuous feed of the sheet.

4. An apparatus of the class described, including a series of overhead rolls arranged to support a sheet of material draped or festooned to form a plurality of depending loops having free lower ends, means for arranging the rolls different distances apart to vary the width of the space between the sides of the loops, means for rotating the rolls for continuously feeding the sheet, and means for varying the frictional contact between the sheet and the feeding means for varying the length of the loops without interrupting the feed of the sheet.

5. An apparatus of the class described, including overhead rolls arranged to support a sheet of material draped or festooned to form a series of depending loops having free lower ends, the rolls being arranged to continuously feed the sheet, and separate manually operable means associated with the rolls for interrupting the feed of any individual roll without interrupting the feed of the sheet to vary the length of the loops and take up any overflow or run of the material in the said loops.

6. An apparatus of the class described including overhead rolls arranged to support a sheet of material draped or festooned to form a series of depending loops having free lower ends, means for rotating the rolls to continuously feed the sheet, separate manually operable means associated with the rolls for varying the frictional contact of the sheet with any individual roll without interrupting the feed of the sheet to vary the length of the loops and take up any overflow or run of the material in the said loops, and fixed transverse bars extending through the upper portions of the loops in spaced relation with the feed rolls and coacting with the said devices for retarding the feeding of the sheet.

7. An apparatus of the class described, including overhead feed rolls arranged to support a sheet of material draped or festooned to form a plurality of depending loops having free lower ends, said feed rolls being provided with reversely arranged spiral ribs extending from the centers to the ends of the rolls to spread a sheet laterally, means for rotating the rolls to continuously feed the sheet during the drying or vulcanizing operation, fixed drag-bars extending through the upper portions of the loops and provided with reversely arranged diverging ribs to spread or stretch the sheet laterally.

8. An apparatus of the class described, including overhead feed rolls arranged to support a sheet of material draped or fes-

- tooned to form a plurality of depending loops having free lower ends, said feed rolls being provided with reversely arranged spiral ribs extending from the centers to 5 the ends of the rolls to spread a sheet laterally, means for rotating the rolls to continuously feed the sheet during the drying or vulcanizing operation, fixed drag-bars extending through the upper portions of the 10 loops and provided with reversely arranged diverging ribs to spread or stretch the sheet laterally, and separate manually operable devices including transverse rods extending through the upper portions of the loops 15 between the feed rolls and the fixed drag-bars and movable to partially lift the sheet from the feed rolls to interrupt the feed of the sheet to the individual loops for varying the length of the latter.
- 20 9. An apparatus of the class described including overhead feed rolls arranged to support a sheet of material draped or festooned to form a plurality of depending loops having free lower ends, means for rotating the rolls to feed the sheet, fixed transverse drag bars extending through the upper portions of the loops and engaging the sheet at one side of each of the loops, pivotally mounted plates supporting the fixed drag bars and movable to adjust the fixed drag bars toward and from the other side of the loops, and clamping means for engaging the pivoted plates to secure the same in their adjustment.
- 25 30 35 10. An apparatus of the class described, including hangers arranged in pairs, overhead feed rolls mounted in the hangers and arranged to support a sheet of material draped or festooned to form a plurality of depending loops having free lower ends, plates pivotally mounted on the hangers at one side thereof and having depending portions, fixed drag bars mounted in the depending portions of the plates and extending through the upper portions of the loops in spaced relation with the feed rolls, and clamping means mounted on the hanger at the other side thereof and connected with the pivoted plates for securing the latter in 40 their adjustment.
- 45 50 55 60 65 11. An apparatus of the class described including overhead feed rolls arranged to support a sheet of material, draped or festooned to form a plurality of depending loops having free lower ends, transverse rods extending through the upper portions of the loops in spaced relation with the feed rolls, and manually operable means for moving the transverse rods substantially in 65 the arc of a circle with respect to the feed rolls to partially lift the sheet from the feed rolls for interrupting the feed of the sheet to the individual loops without interrupting the feed of the sheet through the apparatus.
12. An apparatus of the class described including a plurality of overhead feed rolls arranged to support a sheet of material draped or festooned to form a plurality of depending loops having free lower ends, arcuate guides located adjacent the rolls, transverse rods extending through the upper portions of the loops and operating in the guides, fixed toothed segments concentric with the guides, and gears mounted on the rods and meshing with the segments and adapted to move the rods in the guides when the said rods are rotated, whereby the sheet is lifted from the feed rolls to interrupt the feeding of the sheet to the individual loops without interrupting the feed of the sheet through the apparatus. 70 75 80
13. An apparatus of the class described including a plurality of overhead feed rolls arranged to support a sheet of material draped or festooned to form a plurality of depending loops having free lower ends, arcuate guides located adjacent the rolls, transverse rods extending through the upper portions of the loops and operating in the guides, fixed toothed segments concentric with the guides, and gears mounted on the rods and meshing with the segments and adapted to move the rods in the guides when the said rods are rotated, whereby the sheet is lifted from the feed rolls to interrupt the feeding of the sheet to the individual loops without interrupting the feed of the sheet through the apparatus. 85 90 95
14. The combination with rolls disposed to admit of draping sheet material thereover to provide loops and means for rotating the rolls to feed the material thereover, of means for varying the frictional contact between the material, and a roll to admit of varying the length of a loop without stopping or changing the speed of the roll. 105 110 115
15. The combination with rolls disposed to admit of draping sheet material thereover to provide loops and means for rotating the rolls to feed the material thereover, of a vertically movable member engaging a reach of the loop, and manually operable means for lifting the said member to vary the frictional contact of the sheet with the roll to vary the feed and length of the loop of the sheet without stopping or changing the speed of the roll. 120
16. The combination with rolls disposed to admit of draping sheet material thereover to provide loops and means for rotating the rolls to feed the material thereover, of a vertically movable member engaging a reach of a loop, a toothed element, a pinion carried by the said member and in mesh 125 130

with the toothed element, and means for rotating the pinion to effect a lifting of the movable member and portion of the sheet passing thereover to vary the length of the loop.

⁵ In testimony whereof I have hereunto set my hand, this 5th day of April, 1929.

GEORGE H. KNOWLTON.
